Atty's.

UNITED STATES PATENT OFFICE.

JOHN HARRIS, OF CLEVELAND, OHIO.

BLOWPIPE.

Application filed June 30, 1923. Serial No. 648,667.

To all whom it may concern:

Be it known that I, JOHN HARRIS, a citizen of the United States, residing at Cleveland, in the county of Cuyahoga and State 5 of Ohio, have invented a certain new and useful Improvement in Blowpipes, of which the following is a full, clear, and exact description, reference being had to the accompanying drawings.

This invention relates to blow pipes for cutting and welding with gaseous fuel, and more particularly to the means for forming the mixture of oxygen with combustible gases. It is the general purpose and object 10 of the invention to provide a construction and arrangement of the parts of the blowpipe head which will enable such head to be pressed into shape, instead of being formed of cast metal, thus eliminating the presence of sand holes, which frequently 15 cause the leakage and escape of the high-pressure gases used in such heads. A further object of the invention is to enable the mixing of the oxygen and the combustible 20 gases to be accomplished in a most efficient manner and with a minimum liability of flashing back. I accomplish these objects in and through the construction and arrangement of parts shown in the drawings 25 forming a part of this application, wherein Fig. 1 is a side elevation of a cutting blowpipe or torch embodying my invention; Fig. 2 a sectional view corresponding to the line 2—2 of Fig. 1; Fig. 3 a plan view 30 of the blowpipe or torch shown in the preceding views; Fig. 4 a sectional view corresponding to the line 4—4 of Fig. 3; Fig. 5 a sectional view taken on the plane 35 of the line 5—5 of Fig. 1, looking in the direction of the arrows; and Figs. 6 and 7 are sectional details, corresponding to the 40 lines 6—6 and 7—7, respectively, of Fig. 4.

Describing the various parts herein by reference characters, 1 denotes the head of a blowpipe, the particular head and blowpipe shown herein being employed for the cutting of metal. This head is provided at its lower front end with a cylindrical chamber 2 and has its lower end externally 45 threaded, as indicated at 3.

Projecting rearwardly from the chambered portion of the head is a narrow block portion 4 having near the top thereof a horizontal passage 5 communicating at its front end with a passage 6, which in turn 50 communicates with the central bore 8 of the

inner tip member 7, which member has an externally threaded end 9 by means of which it is threaded into a recess 10 extending upwardly from the chamber 2. The 60 inner tip member is provided with a cylindrical projection 11 which extends into the chamber 2 and is adapted to fit within the cylindrical upper end of the outer tip member (to be described hereinafter). The 65 cylindrical projection is provided with a plurality of slots 12 (four such slots being shown in Fig. 6), each slot extending the full length of the projection and being preferably rectangular in shape. Below the projection 11, the inner member is provided with a projection 13, generally tapered. The lower end of the bore 8 is reduced, as shown at 8^a, and the tapered projection 13 70 is provided with a plurality of slotted passageways 14 surrounding the bore 8^a.

The slotted passageways 12 are arranged on opposite sides of the projection 11, and this projection is flattened for a short distance at opposite sides thereof, as indicated 75 at 11^a, below the nut by which the outer tip member is secured in place.

Fitting within the lower end of the chamber 2 and contacting with the projections 11 and 13 of the inner member is the outer tip member, indicated generally at 15. The upper portion of the outer tip member is cylindrical and fits closely within the chamber 2, while the lower end fits snugly about the tapered lower end of the inner member. The outer member is secured in place by means of a nut 16 threaded on the lower 80 end of the head and having a shoulder 17 projecting inwardly and engaging the outer tip member, there being a tapered packing 85 ring 18 (preferably of copper) carried by the inner portion of the shoulder 17 and forced thereby into a tapered seat 19 provided within the lower end of the head 3.

Below the nut 17, the outer tip member 90 is pressed inwardly on opposite sides thereof, as indicated at 15^a, to provide a pair of inwardly extending lugs or locking members 95 engaging the flattened surfaces 11^a of the inner member and locking the two members 105 securely together.

The detailed construction of the two tip members and the manner of mounting the same is set forth in my application No. 615, 110 189, January 27, 1923; and it is shown herein as presenting the best manner in which I now contemplate applying my invention.

With the parts arranged as described, it will be evident that oxygen for cutting purposes will be supplied through the passages 5 and 6 to the central bore of the tip and 5 that a mixture of gases will be conducted through the passages 12, the annular chamber 20, and the passages 14, to the delivery end of the tip. The manner in which the mixture of the oxygen and combustible gas 10 is formed will now be described:—

21 denotes an upwardly inclined passage in the rear block 4 of the head and 22 is a similarly arranged but longer passage in said block. The passage 21 is for oxygen and 15 the passage 22 for the combustible gas. Projecting from the block portion of the head is a lateral extension 23 which carries the plug and the mixing chamber and the passageway which communicates with the chamber 20. 2. The projection 23 is provided with a threaded bore 24 extending downwardly and inwardly from the top thereof and having a chamber 25 below the threaded portion thereof from which chamber a passageway 25 extends downwardly and inwardly, discharging into the chamber 2. The passage 21 has a lateral branch 21^a which communicates with the bore 24 and the passage 22 a lateral branch 22^a which communicates with 30 the upper portion of the chamber 25.

Mounted in the bore 24 is an injector plug 27 having a head 28 adapted to engage a washer 29 interposed between the said head and the top of the projection 23. This plug 35 is provided with a cross port 29 which receives the oxygen supplied through the passageway 21^a and delivers the same to the bore 30 which extends to and through the bottom of the plug. The lower end of the 40 plug is tapered, as shown at 27^a, and the delivery end of the passage 22, 22^a communicates with the chamber 25 at the top of this tapered portion. Pipes 31, 32 and 33 are connected to the block 4 to deliver respectively oxygen to the passage 5, oxygen to the passage 21, 21^a and combustible gas to the passage 22—22^a.

By the manner of constructing the head, the latter may be made to receive an injector 50 plug and to be provided with a mixing chamber and mixing passage; and the head may be made of pressed or extruded metal, thus eliminating sand holes. Furthermore, this construction enables me, with the same 55 depth of head block 4, to provide a longer mixing passageway 26 than where the mixing tubes formed directly within the central portion of the head block, as shown in my Patent No. 1,408,194, issued February 28, 1922, and this longer passageway insures a complete mixture of the gases supplied to the passageways 20.

Having thus described my invention, what I claim is:—

65 1. A blowpipe comprising a head having

in the front thereof a mixing chamber, and a tip provided with passageways communicating with such chamber and extending downwardly therefrom, the said head having a block extending rearwardly therefrom 70 with a passage for oxygen and a passage for combustible gas in said block, and the said block having at one side of the passages therein a passageway extending downwardly and inwardly and delivering into said 75 chamber, the passages in said block communicating with the passageway therein.

2. A blowpipe comprising a head having in the front thereof a chamber and a tip provided with passageways communicating with such chamber and extending downwardly therefrom, the said head having a block extending rearwardly therefrom with a passage for oxygen and a passage for combustible gas in said block, and the said block 80 having at one side of the passages therein a projection having a downwardly extending bore with a chamber communicating with the lower end of said bore and a passageway extending downwardly and inwardly from said chamber and delivering into the first mentioned chamber, an injector plug threaded into said bore and having a central bore discharging into the second chamber and provided with a port communicating 85 with the upper portion of said bore and with one of the aforesaid passages in said block, the other passage in said block communicating 90 with the second chamber.

3. In a blowpipe, the combination of a head having a chamber in the lower end thereof and a tip extending downwardly from said chamber and having passageways, and means for supplying a mixture of oxygen and combustible gas to said chamber, said means comprising a block extending rearwardly from the head and having therein a passage for oxygen and a passage for combustible gas, the said block having a projection, at one side of the said passages, having a downwardly and inwardly directed bore having its upper portion internally threaded and having a chamber in its lower portion with a downwardly and inwardly extending passageway leading from said chamber to the first mentioned chamber, the passages in said block having lateral extensions communicating with said bore and with the lower or chambered portion thereof, and an injector plug in said bore having itself a central bore adapted to receive gas from the upper passage in said block.

4. A blowpipe comprising a pressed metal head having a lateral projection provided with a mixing passageway and having passages for oxygen and a combustible gas communicating with said passageway, and a tip carried by said head and having one or more passages receiving the mixture formed in 125 said passageway.

5. A blowpipe comprising a pressed metal head having a mixing chamber and a tip provided with passageways communicating with such chamber and extending downwardly therefrom, the said head having a block extending rearwardly therefrom with a passage for oxygen and a passage for combustible gas in said block, and the said block having at one side of the passages therein a projection having a passageway extending downwardly and inwardly and delivering into the mixing chamber, and means for delivering to the passageways in said head the gases supplied through the passages therein. 10
15

In testimony whereof, I hereunto affix my signature.

JOHN HARRIS.
